UNITED STATES PATENT OFFICE.

ERD V. CROWELL, OF LOS ANGELES, CALIFORNIA.

GAS-ENERGY-CONTROL HEAD FOR OIL WELLS.

Application filed March 31, 1923. Serial No. 629,198.

This invention relates to a gas energy control head of the type shown in my prior Patent No. 1,354,027, patented Sept. 28, 1920, and the present invention is an improvement over the invention therein contained.

The object of the present invention is to provide a gas energy control head of the character set forth and having the advantages enumerated in the prior patent referred to but which is simplified in its construction and in its operation and wherein the valve means utilized for controlling the escape of the gas is under the complete control of the inner tubing, said valve being positively connected with the inner tubing and being cooperative with the control head to carry out an efficient control of the gas energy contained in or present with the oil.

Other objects and advantages of the invention reside in certain novel features of the construction, combination and arrangement of parts which will be hereinafter more fully described and particularly pointed out in the appended claims, reference being had to the accompanying drawings forming a part of this specification, and in which:

Figure 1 is a side elevation of a device embodying my invention, showing the same in use, with the valve open;

Figure 2 is a similar view, with the valve closed;

Figure 3 is an enlarged central longitudinal section through the device;

Figure 4 is a plan view of the same;

Figure 5 is a horizontal section taken on line 5—5 of Figure 3; and

Figure 6 is a detail perspective view of the spider of the control head.

In the drawings wherein for the purpose of illustration is shown a preferred embodiment of my invention, the numeral 10 designates an outer casing, extending downwardly to the cap rock.

Arranged within the lower end of the outer casing is a tubular anchor 11, extending through the cap rock into the gas sand.

A tubular anchor packer 12 is arranged within the outer casing and secured to the anchor 11. The numeral 13 designates an inner tubing having a substantially smaller diameter than the outer casing 10, and arranged above the anchor packer 12.

My improved gas energy control head is

arranged between the tubing 13 and the anchor packer 12, and is designated as a whole by the numeral 14. This head or device comprises a tubular body portion having both ends open, the lower end being screw threaded at 16 for engagement with a coupling 17 secured to the anchor packer 12.

A spider is arranged within the tubular body portion 15 and includes a tubular hub 22 and radial arms 23 rigidly secured to the hub and having screw threaded engagement with internal screw threads 24 of the tubular body portion, while its hub is internally screw threaded to engage with the screw threaded portion of a tubular nipple 26. This tubular nipple is rotated to raise and lower it with relation to the tubular body portion 15. The tubular nipple 26 is rigidly connected with the tubing 13 by a coupling 27 or the like.

The upper end of the tubular body portion 15 of the control head is provided with a ground tapered valve seat 30 with which a valve 31 coacts to control the escape of gas through the upper end of the control head. This valve 31 is of annular construction and the opening or bore thereof is threaded for engagement with the upper portion of the threaded nipple 26 as clearly shown in Figure 3. With this arrangement the valve 31 is positively connected to the tubing 13 and does not move relatively to the tubing although of course it may be adjusted on the nipple.

In operation, when the several parts of the apparatus are suitably connected to be lowered into the casing 10, the tubing 13 and consequently the nipple 26 is rotated counterclockwise as viewed from above so as to elevate the nipple and consequently elevate the valve 31. With this valve open the oil and gas may not only flow up through the inner tubing 13 but may also pass upwardly through the control head around the valve 31 and up through the casing 10 on the outside of the tubing 13. When the flow of oil decreases, which may be due to the decrease in gas pressure or to decrease in the volume of oil to trap the gas pressure, the tubing 13 is rotated and consequently the nipple 26 is rotated in a clockwise direction as viewed above so as to lower the nipple 26 and consequently lower the valve 31 to bring the same into engagement with its seat 30 whereby to close the upper

end of the control head and prevent the escape of oil and gas therefrom. With this arrangement the oil and gas is constrained to flow up through the nipple 26 and inner 5 tubing 13 and an efficient flow is obtained since the gas energy is conserved and regulated to the best advantage.

It is to be understood that the form of 10 my invention herewith shown and described is to be taken as a preferred example of the same, and that various changes in the shape, size and arrangement of parts may be resorted to without departing from the 15 spirit of my invention, or the scope of the subjoined claims.

An important feature of the present invention relates in the provision of the single valve 31 positively though adjustably connected to the tubing and cooperable with 20 the valve seat of the control head in the manner described.

Sometimes, oil and gas is found in cavernous strata, instead of porous sand bodies. In such cases, the oil and water has free 25 movement through the lime strata, and the oil is not definitely segregated in the lime, above the water "by gravity", as it is common to find them separated in a true sand. And in such instances, it is common for the 30 water to choke the oil away from the well bore, and the well flows water. It has been found in practice, that by choking the well in, at surface, the invasion of the water is delayed, and the well flows oil. And it is 35 common practice to choke the well in on top.

Now, with this device, means is provided 40 for positively and definitely pre-determining and regulating the degree of opening, through which the well may flow.

Also the regulation of "flow", is down 45 close to the source of "flow energy" (which is the expansion of gas), so that the regulation is bound to be more positive, a desirable result.

I claim:

1. In a device of the character described 50 for use with oil and gas wells, discharge tubing, a packer associated with the discharge tubing and having anchoring means controlled by the discharge tubing, a control head arranged upon the packer, and co-operative valve means carried by the control head and discharge tubing for posi-

tively and definitely regulating the degree 55 of opening through said valve means.

2. In a device of the character described 60 for use with oil and gas wells, discharge tubing, a packer associated with the discharge tubing and having anchoring means, 65 a control head arranged upon the packer, and co-operating valve means carried by the control head and discharge tubing providing means for pre-determining and definitely regulating the degree of valve opening.

3. In a device of the character described, 70 a control head including a tubular body portion adapted to be connected with the anchor packer arranged within the casing of an oil well, tubing extending down into the oil well and having a nipple connected to its lower end and extending into the tubular body portion of the control head, a spider 75 connected with the control head and having a hub provided with internal screw threads, the periphery of the nipple being provided with screw threads engageable with the internal screw threads of the head of the spider whereby as the tubing is turned the nipple and tubing are longitudinally shifted with respect to the control head, the upper end of the control head being provided with a valve seat, and a single valve of annular form and having its opening provided with screw threads and engageable with the screw threaded nipple whereby the valve is adjustable on the nipple though normally constrained to rotate therewith and partake of the motion thereof, the valve being cooperable with the valve seat of the control head.

4. In a control device for oil and gas wells, a head for coupling with a packer, 95 said head having a valve seat and an escape port at its upper end, a tubular member having screw threaded engagement in the head and adapted to be connected with a discharge tubing, and a valve immovably fastened on the tubular member and adapted 100 to engage the seat of the head, said valve being adjusted to and maintained at, a definite distance from its seat, by a positive rotation of the tubular member, whereby the flow of fluid between the valve and its seat may be controlled to a definite and predetermined degree.

ERD V. CROWELL.
